Dallas, Tex.

Application October 30, 1945, Serial No. 123,318

Term of patent 3½ years

(Cl. D17—6)

To all whom it may concern:

Be it known that we, Charles E. Seale, Jr., and Leslie W. Stinne, citizens of the United States, residing at Dallas, in the county of Dallas and State of Texas, have invented a new, original, and ornamental Design for a Clothespin, of which the following is a specification, reference being had to the accompanying drawing, forming part thereof.

Figure 1 is a perspective view of a clothespin showing our new design.

Figure 2 is a top plan view thereof.
Figure 3 is a side elevational view, and
Figure 4 is a front end elevational view of the clothespin.

We claim:

The ornamental design for a clothespin, as shown.
